UNITED STATES PATENT OFFICE.

ROBERT C. LANPHIER, OF SPRINGFIELD, ILLINOIS, ASSIGNOR TO SANGAMO ELECTRIC COMPANY, OF SPRINGFIELD, ILLINOIS, A CORPORATION OF ILLINOIS.

INDUCTION-METER.

1,010,272.

Specification of Letters Patent. Patented Nov. 28, 1911.

Application filed March 30, 1911. Serial No. 617,904.

To all whom it may concern:

Be it known that I, ROBERT C. LANPHIER, a citizen of the United States, residing at Springfield, in the county of Sangamon, State of Illinois, have invented certain new and useful Improvements in Induction-Meters, of which the following is a specification, reference being had to the accompanying drawings.

10 This invention relates to induction meters of the type employing the principle of the split phase rotating field, and it has for its object to provide a new and improved construction and arrangement of parts as hereinafter pointed out. In the commercial use of induction meters, it is quite often necessary to replace shunt or series coils and it is one of the objects of this invention to provide a construction which shall permit of 20 the ready removing and replacing of such coils. In meters of this type, it is usual to employ permanent damping or braking magnets, which must of course be maintained of constant strength if the meter is to 25 continue to measure accurately. Care must therefore be taken to guard these magnets against the demagnetizing effect of a very heavy field created by the series magnet upon the passage of an extraordinarily 30 heavy current through the series coil due to a short circuit or other cause.

It is one of the objects of this invention to prevent,—by the arrangement of the field structure itself, and without the assistance of 35 any special shielding device, the demagnetizing effect of heavy fields produced by short circuits or otherwise.

It is another object of this invention to improve the construction of the parts so that 40 I am enabled to place the field magnets in closer relation to each other about the periphery of the armature, thus securing a greater reaction between such fields and consequently securing a greater torque.

45 It is another object of this invention to improve the construction and arrangement of meters of this class in sundry details hereinafter pointed out.

The means by which I have accomplished 50 these objects are illustrated in the drawings and hereinafter specifically described.

That which I believe to be new is set forth in the claims.

In the drawings,—Figure 1 is a horizontal cross-section on line 1—1 of Fig. 2; Fig.

2 is a vertical section on line 2—2 of Fig. 1; Fig. 3 is a view of the inside of the base-plate with the grid, the parts supported by it, and the front portion of the meter removed; Fig. 4 is a view of the supporting 60 grid attached to the base-plate and seen from the inner side or side which faces the inner surface of the base-plate shown in Fig. 3; Fig. 5 is a diagrammatic view of a side elevation of the working parts of the 65 meter; Fig. 6 is a diagrammatic view showing the parts shown in Fig. 1, viewed from the front or right-hand side, with the damping magnets removed; and Fig. 7 is a dia- 70 grammatic top or plan view of the parts shown in Fig. 5 with the disk broken away and with the windings and coil connections omitted.

Referring to the drawings,—10 indicates the base or back-frame of the meter. 11 75 indicates a coil mounted upon a core 12 removably secured to said plate 10 and preferably made up of a number of thin plates suitably connected together, each of said plates being stamped out in substantially a 80 rectangular form as indicated in Fig. 3. The coil 11 contains a large number of turns of fine wire, said coil being connected across the circuit as indicated in said figure. As shown in Fig. 1, the ends of said coil are 85 electrically connected to binding-posts 13—14, the latter of which is connected electrically by a wire 15 to a binding-post 16. The two poles of the magnet are indicated by 17 and 18. The poles are close together, 90 leaving just sufficient clearance for the free rotation of the disk armature hereinafter described.

19 indicates a support or grid which ex- 95 tends across the meter parallel with the base 10, being spaced a proper distance from said base 10 by means of posts 20 formed integral with the base 10, or otherwise suitably secured thereto, to the free end of which the grid 19 is secured, as by screws 20.

21 indicates a coil mounted upon a core 22 suitably secured to the grid 19 and prefer- 10 ably made up of a number of thin plates suitably connected together, each of which is stamped out in the shape of a U. The coil 21 consists of only a few turns of coarse wire connected in series with the main load circuit. As shown in Fig. 2, the coil 21 is made in two parts, one upon each arm of the core 22. The ends 23—24 of the coil 21 are 11

in use connected respectively to the binding-post 13 and a binding-post 25. The poles of the laminated core 22 are indicated by 26-27.

5 28 indicates the disk armature of the meter, formed of aluminum or other suitable material, mounted upon the shaft 29, which is of any approved type, and is carried by brackets 40-41 projecting from the outer 10 face of the grid 19. The disk, whose shaft is mounted on the outside of the grid 19, projects through a suitable slot therein, as 19*, as is best seen in Figs. 1 and 4.

15 30 indicates one of the two permanent damping magnets between which the disk 28 rotates, and which is carried by suitable brackets, as 42, projecting from the front face of the grid 19.

20 31 indicates a return plate suitably secured to the support 41 and preferably made up of a number of thin plates suitably connected together, each of which is stamped out in the shape of a U. The ends 32-33 of the return plate 31 are located directly 25 on the opposite side of the disk 28 from the poles 26-27 of the series magnet, as shown in Fig. 2.

It will be understood that with the grid 19 placed upon the base 10 with the surface 30 shown in Fig. 2 facing said base 10, the disk 28 will enter the space between the poles 17 and 18 of the shunt magnet, the pole 17 coming between and embraced by the ends 32-33 of the return plate, and the pole 18 35 coming between the poles 26-27 of the series magnet, all as shown in Figs. 1 and 2 and as shown diagrammatically in Figs. 3, 4 and 5.

The operation of my improved meter is 40 well understood by those skilled in the art and need not be described herein. It is believed to be sufficient to point out that the interposition of the laminated return plate between the electromagnets and the permanent damping magnets, with the laminations 45 vertical to the plane of the disk in a curve corresponding substantially with the curves of line of force in a spreading field produced by the series magnet, is effective 50 to cause such magnetic field to be taken up and absorbed before the field can spread to the permanent magnets and affect them appreciably.

Another advantage of my construction 55 and arrangement, and especially of having the return plate in the form of a U, is the possibility of placing the poles 26 and 27 of the series magnet at a maximum distance from the shaft 29 and at the same time in 60 close proximity to the poles 17-18 of the shunt magnet, which manifestly could not be accomplished if the return plate were not of curved or U shape. This is of great importance, since it enables me to obtain the 65 maximum effect of interaction between the

field produced by the series magnet of one phase and the field of a different phase produced by the shunt magnet, as will be readily understood.

While it will be understood that a difference in phase is produced in the coils 11 and 21 by the construction of the coils themselves, one being of a greater number of turns of fine wire and the other being of a few turns of coarse wire, I do not limit myself to attaining the difference in phase necessary for the proper operation of the meter by this means, except as hereinafter claimed.

It will be seen from the above description that I have produced an induction motor meter having a number of advantages, both structural and electrical. By reason of the construction shown I am enabled to use a shunt magnet with a single air-gap embracing the plate close to its periphery and, therefore, as far as possible from the center of the plate radially and operating to the best advantage, coupled with a series magnet which, with its return plate, has two air-gaps, one upon each side of the poles of the series magnet, and also lying close thereto and therefore most effective for interaction therewith and also at a maximum radius from the center of the disk; at the same time the curved, bent or general U-shaped return plate for the series magnet enables it to embrace the mass of one of the poles of the shunt magnet so that its ends lie over the ends of the series magnet and close to the poles of the shunt magnet. The curved structure, therefore, of this return plate is the means by which I am enabled to gain the electrical advantage of having the pole of the series magnet operating at the same radial distance on the armature as the pole of the series magnet and close to the mass of the poles of the series magnet. By constructing this return plate of strips fastened together, whose laminations are vertical to the plane of the disk, and by giving it a general bend or U shape so that it projects well out from the fields of the series magnets toward the permanent magnets, obtain a construction which causes the return plate to absorb the spreading lines of force arising under short circuiting conditions where there is a great and sudden flow through the magnet, which would otherwise spread out past the permanent magnets and seriously affect and impair their magnetism without the interposition between the energizing magnets and the permanent magnet of any exterior structure for that purpose and this results because the spreading lines of force under short circuit conditions will naturally tend to travel along the curved lines defined by the laminations of the return plate. As the front of the return plate is well forward of the plane of the seri

magnet in the direction of the progression of these spreading lines of force under short circuit conditions, no spreading lines of force will be left to act upon and weaken the permanent magnets. Further, by my improvements I am enabled to construct a meter which possesses a number of mechanical advantages. By removably securing the shunt magnet to the back-plate, by providing a grid held at a suitable distance from the back-plate by suitable mountings, and by mounting upon this grid a series magnet and its connections, the armature and armature bearings, and the permanent magnets, 5 I have devised a structure which may be readily taken apart for purposes of repair, is readily accessible, and in which the weight of the permanent magnets, the series measuring elements and the return plate are all 10 carried upon the grid and upon suitable brackets thereupon. I have produced a small and compact induction meter, and, as has been said, one that can be readily taken apart and repaired and in which the parts 15 are all readily accessible. It also enables me to produce a type of meter in which, if the shunt or potential coil breaks down or burns out on account of abnormal line conditions or accident, the replacement of the 20 coil is an easy and convenient matter. By simply removing the front grid and its attached parts the shunt magnet as an entirety may be easily removed and a new core and coil substituted for it.

15 I have shown and described the return plate of the series magnet as "curved" or U shape. Of course it will be understood that I do not limit myself to a true continuous curve of the type shown, but use the 25 word "curve" only in its general sense as describing a laminated return plate which is curved or bent or shaped so that its ends, which are in register with the poles of the series magnet, may at the same time embrace 30 between them the pole of the shunt magnet, while between its ends the return plate extends outward away from the magnetic poles so that its front—that is, the side away from the poles—lies well forward of the poles of 35 the series and shunt magnet. I therefore use the word "curved" in a broad sense as applying to a return plate having substantially this construction, whether it be a continuous curve or some other substantially 40 equivalent shape.

That which I claim as my invention, and desire to secure by Letters Patent, is,—

1. In an alternating current meter, in combination, a rotative metallic armature, shunt 45 and series wound electro-magnets in coöperative relation, one of said magnets having a single air-gap embracing the edge of said armature at a maximum radius, the other having two air-gaps embracing the armature 50 on each side of the air-gap of the first mag-

net and at a maximum radius of the disk, said second magnet having a return structure embracing the mass of said first magnet between the ends of said return structure.

2. In an alternating current meter, in combination, a rotative metallic armature, an electro-magnet having windings adapted to be connected in shunt with an alternating current circuit and having a single air-gap embracing the edge of said armature at a maximum radius thereon, a second electro-magnet having windings adapted to be connected in series with an alternating current circuit and having two air-gaps embracing said armature on each side of the air-gap of said shunt magnet and at a maximum radius of the armature and provided with a return magnetic structure embracing the mass of said shunt magnet between the ends of said return structure. 70

3. In an alternating current meter, in combination, a rotative metallic armature, an electro-magnet having windings adapted to be connected in shunt with an alternating current circuit and having a single air-gap embracing the edge of said armature at a maximum radius thereon, a second electro-magnet having windings adapted to be connected in series with an alternating current circuit and having two air-gaps embracing said armature on each side of the air-gap of said shunt magnet and at a maximum radius of the armature one portion of said second magnet being a return magnetic structure consisting of curved plates with their laminations vertical to the plane of the armature and bent with their concave side toward said magnet and embracing the mass of said shunt magnet between the ends of said return structure. 80

4. In an alternating current meter, in combination a rotative disk armature, a magnet adapted to be energized by current from an alternating current circuit and embracing said disk between its poles near the periphery of said disk, a second magnet adapted to be energized by current from an alternating current circuit and having its poles on one side of said disk upon each side of one of the poles of said first magnet and near the periphery of said disk, a return-piece for said second magnet on the other side of said disk and extending from one pole to the other of said second magnet in a curve concave toward said first magnet poles. 100

5. In an alternating current meter, in combination a rotative disk armature, a magnet adapted to be energized by current from an alternating current circuit and embracing said disk between its poles near the periphery of said disk, a second magnet adapted to be energized by current from an alternating current circuit and having its poles on one side of said disk upon each side of one of the poles of said first magnet and 110

120.

125

130

near the periphery of said disk, a braking magnet in operative relation with said disk armature, a return-piece for said second magnet on the opposite side of the disk from the poles thereof between said first magnet and said braking magnet and curved or bent with its concave side toward said first magnet poles.

6. In an alternating current meter, in combination, a rotative disk armature, a magnet embracing said disk between its poles near the periphery of said disk, windings for said magnet adapted to be connected in shunt across an alternating current circuit, a second magnet having its poles on one side of said disk upon each side of one pole of said first magnet and near the periphery of said disk, windings for said magnet adapted to be connected in series with an alternating current circuit, a return-piece for said second magnet, a return-piece for said second magnet between the poles thereof and extending in a curve concave toward said first magnet.

7. In an alternating current meter, in combination, a rotative disk armature, a magnet embracing said disk between its poles near the periphery of said disk, windings for said magnet consisting of a relatively large number of turns of relatively fine wire adapted to be connected in shunt across an alternating current circuit, a second magnet having its poles on one side of said disk upon each side of one pole piece of said first magnet and near the periphery of said disk, energizing windings for said second magnet consisting of a relatively small number of turns of relatively large wire adapted to be connected in series with an alternating current circuit, a return piece for said second magnet extending between the poles thereof on the other side of the disk therefrom and bent to present its concave side toward said first magnet and its convex side toward the center of the disk.

8. In an alternating current meter, in combination, a rotative disk armature, a magnet embracing said disk between its poles near the periphery of said disk, windings for said magnet consisting of a relatively large number of turns of relatively fine wire adapted to be connected in shunt across an alternating current circuit, a second magnet having its poles on one side of said disk upon each side of one pole piece of said first magnet and near the periphery of said disk, energizing windings for said second magnet consisting of a relatively small number of turns of relatively large wire adapted to be connected in series with an alternating current circuit, a return-piece for said second magnet extending between the poles thereof on the other side of the disk therefrom and bent to present its

concave side toward said first magnet and its convex side toward the center of the disk, and a braking magnet in operative relation to said disk beyond the convex side of said curved return piece.

9. In an electricity meter, in combination, a base, an electro-magnet removably secured to said base and adapted to be connected with an electric circuit, a grid, means for removably securing said grid to said base at a suitable distance therefrom, a spindle carried by said grid, a disk armature mounted on said spindle, a second electro-magnet carried by said grid and in coöperative relation with said armature and adapted to be connected with an electric circuit, said spindle, disk and second electro-magnet being so mounted upon said grid that when the grid is placed in position the said disk and electro-magnet are brought into coöperative relation with said first magnet.

10. In an electric motor meter, in combination, a base, an electro-magnet removably supported on said base and having a single air-gap and adapted to embrace a disk armature, said magnet being adapted to be connected with an electric circuit, a grid, means for removably securing said grid to said base at a suitable distance therefrom, a spindle carried by said grid, a disk armature mounted on said spindle, a U-shaped electro-magnet adapted to be connected with an electric current and carried by said grid with its poles facing one side of said disk near the periphery thereof, a return piece carried by said grid on the other side of said disk, said spindle, disk, magnet and return piece being so mounted upon said grid that when the same is placed in position on the base the periphery of the disk will lie in the air-gap between the poles of said first-magnet and the poles of said second magnet will lie upon each side of the polar mass of said first magnet on one side of the disk and the polar mass of said first magnet on the other side of the disk will be embraced between the ends of the return piece.

11. In an electric motor meter, in combination, a base, an electro-magnet removably supported on said base and having a single air-gap and adapted to embrace a disk armature, said magnet being adapted to be connected with an electric circuit, a grid, means for removably securing said grid to said base at a suitable distance therefrom, a spindle carried by said grid, a disk armature mounted on said spindle, a U-shaped electro-magnet adapted to be connected with an electric circuit and carried by said grid with its poles facing one side of said disk near the periphery thereof, a curved return piece carried by said grid on the other side of said disk with the concave side toward the periphery of the disk and

consisting of laminations vertical to the plane of the disk, said spindle, disk, electro-magnet and return piece being so mounted on said grid that when the same is in position on the base the periphery of the disk will lie in the air-gap between the poles of said first magnet, the poles of said second magnet will lie upon each side of one pole of said first magnet upon one side of the 10 disk and the ends of said return piece will lie upon each side of the other pole of said first magnet on the other side of said disk.

12. In an alternating current meter, in combination, a base, a magnet removably secured thereto and having a single air-gap and adapted to be connected to an alternating current circuit, a grid, means for removably securing said grid to said base at a suitable distance therefrom, a U-shaped 20 electro-magnet supported by said grid and adapted, when said grid is placed in position, to have its pole pieces close by the side of the poles of said first magnet, a return plate for said second magnet supported by said grid, a revolute shaft supported on one side of said grid by suitable brackets, a metallic disk armature supported by said shaft and having its periphery embraced by the air-gaps between said second magnet 30 and said return plate and adapted, when said grid is placed in position on said base, to also have its periphery lie within the air-gap of said first magnet.

13. In an alternating current meter, in combination, a base, a magnet removably secured thereto and having a single air-gap and adapted to be connected to an alternating current circuit, a grid, means for removably securing said grid to said base at 35 a suitable distance therefrom, a U-shaped electro-magnet supported by said grid and adapted, when said grid is placed in position, to have its pole pieces close by the side of the poles of said first magnet, a return 40 plate for said second magnet supported by said grid and extending in a curve from one pole of said magnet to the other with its concave side facing said first magnet when in position and with its ends lying upon each side of the polar mass thereof, a revolute shaft supported on one side of said grid by suitable brackets, a metallic disk armature supported by said shaft and having its periphery embraced by the air-gaps between said second magnet and said 45 return plate and adapted, when said grid is placed in position on said base, to also have its periphery lie within the air-gap of said first magnet, and a permanent magnet also supported on said grid upon the opposite side thereof from said second-named magnet and embracing said disk in the air-gap between its poles.

concave side facing said first magnet when in position and with its ends lying upon each side of the polar mass thereof, a revolute shaft supported on one side of said grid by suitable brackets, a metallic disk armature supported by said shaft and having its periphery embraced by the air-gaps between said second magnet and said return plate and adapted, when said grid is placed in position on said base, to also have its periphery lie within the air-gap of said first magnet.

14. In an alternating current meter, in combination, a base, a magnet removably secured thereto and having a single air-gap and adapted to be connected to an alternating current circuit, a grid, means for removably securing said grid to said base at a suitable distance therefrom, a U-shaped electro-magnet supported by said grid and adapted, when said grid is placed in position, to have its pole pieces close by the side of the poles of said first magnet, a return plate for said second magnet supported by said grid and extending in a curve from one pole of said magnet to the other with its concave side facing said first magnet when in position and with its ends lying upon each side of the polar mass thereof, a revolute shaft supported on one side of said grid by suitable brackets, a metallic disk armature supported by said shaft and having its periphery embraced by the air-gaps between said second magnet and said return plate and adapted, when said grid is placed in position on said base, to also have its periphery lie within the air-gap of said first magnet, and a permanent magnet also supported on said grid upon the opposite side thereof from said second-named magnet and embracing said disk in the air-gap between its poles.
